UNITED STATES PATENT OFFICE.

RALPH ADAMS, OF FALLS CITY, OREGON.

SPARK-ARRESTER.

1,202,953.

Specification of Letters Patent. Patented Oct. 31, 1916.

Application filed March 6, 1916. Serial No. 82,454.

To all whom it may concern:

Be it known that I, RALPH ADAMS, a citizen of the United States, residing in Falls City, in the county of Polk and State of Oregon, have invented certain new and useful Improvements in Spark-Arresters, of which the following is a specification.

This invention relates to that class of spark arresters in which the smoke and vapors pass to the outlet of the furnace stack through screens of wire cloth which serve to arrest the sparks and enable them to be delivered separately or apart from the smoke and vapors to a suitable receptacle or to the ground.

The object of my invention is to provide a spark arrester of the kind referred to in which an extensive screen surface is afforded which will not unduly retard the draft, and whereby screens of small mesh may be employed.

Another object of the invention is to provide means for producing a strong draft through the flues which will keep the screens clear of soot, etc.

Another object is to provide means for regulating the draft so that when starting the fire, or first getting up steam, a freer draft may be obtained.

My improvements are illustrated in the accompanying drawings in which,

Figure 1 is a view mainly in vertical central section but partly in elevation of a smoke stack with my improvements applied thereto. Fig. 2 is a similar view of a modification.

The hood A of the boiler is provided with a stack B having a reduced portion B' hinged at b to the body of the stack and carrying an outlet pipe B² of reduced diameter. A frustum shaped screen C is mounted in the lower portion of the stack and is preferably circular in cross-section, being wider at the bottom than at the top. It is reinforced at its lower end where it is riveted or bolted to the hood A. The upper end of the screen carries a cap D, the outer edge of which is bolted or riveted to the upper edge of the screen and it is formed with an annular spark-receiving chamber d. The central portion d' of the cap is open and on one side the chamber d communicates with a pipe E leading to the ground or to a suitable receptacle. This pipe is provided with a reticulated portion e which permits the escape of smoke and vapors but past which the

sparks descend. The screen C carries reinforcing rods c which strengthen it. Within the screen C is an inverted cone-shaped screen F, the lower end of which receives the vertical portion g of a bent rod G and by which it is guided vertically. The upper end of the cone is reinforced as shown and is connected to a link h jointed to a lever H pivoted to the stack at h' and connected at its outer end with an operating rod I by means of which the cone may be raised and lowered.

J indicates an exhaust steam pipe from the engine delivering to the stack below the screens and K indicates a similar exhaust pipe delivering to the stack above the screens. Either one or both exhaust pipes may be used to create a strong draft through the stack.

When the parts are in the position shown in Fig. 1 the products of combustion pass into the space between the inner and outer screens. Smoke and vapors pass through the sides of the outer screen and thence rise to the upper portion of the stack and pass out at the delivery end thereof. Smoke and vapors also pass through the inner screen and continue up through the circular opening of the cap and pass out through the stack. The sparks are arrested by the screens and are received by the annular cap D, entering the chamber d and passing out through the pipe E. Steam from the exhaust pipe J passing upwardly through the screens creates a strong draft therein and causes the sparks to be directed against the inclined surfaces of the screens. This has the effect of scraping or rasping the screens and keeping them clear of soot. Steam from the exhaust pipe K creates a draft above the screen and tends to produce a vacuum or a suction which promotes the draft. While I preferably use both exhaust pipes, only one of them need be employed.

When starting the fire, or when "getting up steam," the inner screen cone F may be lowered so as to increase the draft. This may be done by means of the rod I operating upon the lever H in such manner as to lower the screen F and permit the products of combustion to pass more freely out through the opening d' of the cap. After this the rod I may be operated to draw the upper edge of the screen close to the edge of the cap. Any suitable means may be employed for locking the rod I to hold the cone F in place.

In Fig. 2 I have shown a modification. In this case the stack A' delivers to an enlarged upper portion B' which is supported on the lower portion A' by flanges M. 5 The screen C' is attached at its lower end to a ring c' which is supported on the flanges M. The cap D is similar to that shown in Fig. 1 and communicates with a discharge pipe E like that before referred 10 to. The inner cone F is also similar to that before described and it is operated in a similar way. In this case the rod I is shown as being threaded at its lower end i and carrying a nut i'. The lower portion of the 15 rod engages a stop plate i''. These devices may be employed for holding the cone F in its closed position or permitting it to be lowered. The lower portion A' of the stack is shown as being provided with openings 20 a' near its upper end over which are arranged wings or deflectors a against which some of the sparks and vapors strike and are deflected through the openings a' and rise to the outer portion of the screen C'. 25 In this way the draft is somewhat equalized.

My improvements may be applied to locomotives, donkey engines, hoisting engines, traction engines, or in fact all kinds of engines burning any fuel except oil. Experience has demonstrated that a spark arrester 30 constructed in accordance with my invention is most efficient as the draft can be easily regulated, screens of fine mesh may be employed so as to prevent the escape of 35 sparks with the smoke, and the screens may be kept clear of soot inasmuch as they are not exposed to the atmosphere and the sparks are caused to come in contact with the screens in such manner as to exert an 40 abrading or rasping action thereon which keeps them open.

I claim as my invention:

1. A spark arrester, comprising a stack, a frustum-shaped screen within the stack, 45 an inverted cone-shaped screen within the screen first mentioned, a spark-receiving cap above the screens having an annular chamber open at bottom for receiving sparks

passing upwardly between the screens, a pipe connected with said cap for conducting 50 sparks from the stack, a guide rod for the lower end of the cone, and means for raising and lowering the cone toward and away from the spark-receiving cap.

2. A spark arrester, comprising a stack, 55 a frustum-shaped screen within the stack, an inverted cone-shaped screen within the screen first mentioned, a spark-receiving cap above the screens having an annular chamber for receiving sparks passing upwardly 60 between the screens and which is open at bottom and has an inclined top wall, a discharge pipe for sparks connected with said annular chamber, a guide rod for the lower end of the cone, and means for raising and 65 lowering the cone toward and away from the spark-receiving cap.

3. A spark arrester, comprising a stack, a frustum-shaped screen within the stack, an inverted cone-shaped screen within the 70 screen first mentioned, a spark-receiving cap above the screens for receiving sparks passing upwardly between the screens, a steam exhaust pipe delivering below said cone-shaped screen, and a steam exhaust pipe 75 delivering in the stack above said screens.

4. A spark arrester, comprising a stack, a frustum-shaped screen within the stack, an inverted cone-shaped screen within the screen first mentioned, a spark-receiving cap 80 above the screens having an annular chamber for receiving sparks passing upwardly between the screens and a central opening 85 above the top of the cone-shaped screen and which is of substantially the same diameter as the top of the cone-shaped screen, and means for raising and lowering the cone-shaped screen toward and away from said cap.

In testimony whereof, I have hereunto 90 subscribed my name.

RALPH ADAMS.
